UNITED STATES PATENT OFFICE

PERCY C. KEITH, JR., OF BERNARDSVILLE, NEW JERSEY, ASSIGNOR TO THE M. W. KELLOGG COMPANY, OF NEW YORK, N. Y., A CORPORATION OF DELAWARE

METHOD OF DISTILLING OILS

Application filed July 10, 1928. Serial No. 291,608.

This invention relates to a method for distilling hydrocarbon oils and particularly for making lubricating oils from crude petroleum and will be understood from the following description read in conjunction with the drawings in which

Fig. 1 is a side elevation, principally in section, of apparatus in which my method may be carried into effect, and

10 Fig. 2 is a vertical section in detail of part of Fig. 1.

Referring specifically to Fig. 1, the inlet pipe 1, controlled by the valve 2, is adapted to supply crude oil to a tubular heater 3 which is shown diagrammatically in section. This heater consists of a series of tubes joined end to end by cross over connections to form a continuous circuit and will be hereinafter referred to as a pipe still.

20 The pipe still 3 is surrounded by any suitable refractory setting 4, heated through the port 5 by the burner 6. The pipe still discharges through the outlet 3' and the distributor 4' into a separating drum 5'. The pipe 3' and the separating drum 5' are covered by insulation 3a and 6' respectively to minimize heat loss therefrom. The drum 5' carries transverse partitions 7 and 8 located respectively below and above the distributor 4'. 30 These transverse partitions are equipped with conventional vapor distributors such as bell caps and overflow pipes, not shown. The base of the drum carries an overflow pipe 9 which projects upwardly therein to considerable height to permit the accumulation of a body of liquid therein. Any excess over that necessary to maintain this body will escape by flowing downwardly through pipe 9, and by manipulation of the valve 10 may be continuously withdrawn.

The pipe 11 connects to the drum 5' adjacent to the lower portion thereof and discharges into the pump 12 which is adapted to force liquid through the pipe 13 and thereby into the bank of tubes 14 in the refractory setting 4. The pipe 15 is connected to the outlet end of the bank of tubes 14 and is controlled by the valve 16. The arrangement is such that liquid may be continuously withdrawn from the base of drum 5', heated in a

confined stream returned to the body of liquid maintained in the lower part of the drum. The pipes 11, 13 and 15 are covered by thermal insulation 11a, 13a and 15a respectively. Steam may be admitted to the drum 5' by means of a pipe 17 controlled by the valve 18 discharging into the distributor 19.

A vapor outlet pipe 20 leads from the upper part of the drum into the lower part of the rectifying column 21. The column 21 is preferably surrounded by thermal insulation, not shown. The pipe 20 is covered by insulation 20a. The column 21 is equipped with a number of horizontal partitions 22 which carry vapor distributors, bell caps and overflow pipes, not shown. The equipment is such that rectifying conditions may be maintained in the column and provision is made for withdrawing a number of intermediate cuts from the column by means of pots 23, 24, 25, 26 and 27. These pots are provided with the pipes 28, 29, 30, 31 and 32 for the introduction of steam in the same for stripping and the pipes 33, 34, 35, 36 and 37 for carrying away the distillates to be withdrawn from the column. There are two condensing coils 38 and 39 in the upper part of the column. 38 may be supplied with cooling water through the inlet pipe 40 and coil 39 may be supplied with oil through the pipe 41. This is preferably the feed oil for the apparatus, which is thereby preheated and discharged into the pipe 1 whereby it is conducted into the pipe still 3. Any bottoms accumulating in the base of the rectifying column 21 may be continuously or periodically withdrawn through the pipe 42 controlled by the valve 43 to a suitable accumulator. Any vapors arriving in the top of the rectifying column 21 will be conducted away through the pipe 44. The foregoing apparatus is adapted to be operated under vacuum and is preferably operated in this manner. This vacuum is preferably maintained by the operation of a jet ejector or booster 45. This booster is connected with the pipe 46 which discharges into the barometric condenser 47. Condensing water for the barometric condenser is introduced through pipe 48 controlled by valve 49. The booster 45 is adapted to take gases at

55

very low pressures, say from a few millimeters up to fifty and by the action of jets of superheated steam of high velocity to build up the pressure on the outlet side of the 5 booster to say 100 or 200 millimeters at which pressure it can be conveniently and economically handled by the barometric condenser. Steam for the operation of the booster is introduced through the pipe 45a controlled by 10 the valve 45b.

Referring specifically to Fig. 2, the pot 25 is typical of the construction of the members 23, 24, 25, 26 and 27. It consists of an enclosed tank located on one of the horizontal 15 partitions 22 of the tower. It carries a single tray 50 provided with bell caps or equivalent vapor distributors 51 and an overflow pipe 52. Oil is passed on to the partition 51 by means of the pipe 53 controlled by the valve 54 20 which drains oil from the horizontal partition immediately above. Steam is introduced through the pipe 30 controlled by the valve 31, and discharged into the pot 25 through the distributor 55. The steam may 25 be controlled by manipulating valve 31a so as to strip the light ends from any oil discharging through the pipe 53 on to the plate 51 and the stripped oil flows off continuously 30 through the pipe 35. The steam and oil vapors which it carries pass upwardly through the pipe 56 to be discharge above the next higher horizontal partition.

The method of operation of the apparatus is as follows:

35 A crude petroleum is passed into the pipe 41, preheater 39 and pipe 1. The phrase "crude petroleum" or "crude oil" as employed herein denotes either a crude petroleum in its native condition as recovered from the 40 well or a petroleum which has been topped or otherwise fractionated to divest it of lighter constituents. A preferred form of crude oil for my purpose consists in a native crude petroleum from which the gasoline, kerosene 45 and gas oil have been removed leaving a residuum principally of lubricating components. The crude oil is heated in the pipe still 3 by the burner 6 to a temperature sufficient to effect partial vaporization, preferably to a temperature between 600 and 800° F.; this material discharges through the distributor 4' into the drum 5'. Separation takes place in this drum, the vaporized constituents pass upwardly and by means of the 50 vapor outlet 20 are diverted into the rectifying column 21. The unvaporized portions pass downwardly over the partition 7 and are stripped by the introduction of steam, preferably super-heated, through the distributor 19. A liquid residuum accumulates in the base of the drum 5' up to the level of the overflow pipe 9, the excess being continuously withdrawn. The hydrocarbon vapors 55 in the column 21 are continuously rectified 60 under conditions of partial or substantially

complete condensation and a series of intermediate cuts are taken off through the pipes 33, 34, 35, 36 and 37.

My preferred method of operating the column, consists in controlling the cooling medium supplied by coils 38 and 39, so as to produce substantially complete condensation of hydrocarbon vapors in the upper part of the column while permitting substantially all the steam to pass overhead and out 7 through the pipe 44. The absolute pressure in the upper part of the column is maintained at relatively low, say from a few millimeters up to about fifty, and this pressure is built up by means of the jet ejector 45 at the 8 ejector outlet to a pressure of say 75 to 150 millimeters of mercury which may be conveniently taken care of by the operation of the barometric condenser 47.

I have found that a particularly efficient and economical method for operating this distillation consists in continuously abstracting a small quantity of the liquid residuum in the base of the drum 5' and pumping this through the heating coil 14 by which it is elevated in temperature so that the entire body of the residuum in the base of the drum 5' may be held at an optimum temperature regardless of the inevitable thermal losses. This is of value in permitting exact control of the total amount of the crude oil which is to be taken overhead and through the pipe 20 as vapors and resolved into lubricating distillates. It is further of value in permitting the exact control of the consistency of the tar residuum withdrawn through the pipe 9. A still further advantage is that by maintaining this liquid residuum in the bottom of the drum 5' at an elevated temperature, the total yield of lubricating oil from any particular crude may be considerably enhanced. For this purpose, I preferably maintain the residuum in the base of the drum at a temperature of 600 to 800° F. or alternately at a temperature at which hydrocarbon vapors are vigorously and actively developed and the said mixed residuum is evolved therefrom. When operating under relatively low pressures, say less than two hundred millimeters of mercury absolute, and a temperature above 700° F. I find that the tar constituents of the residuum tend to rearrange themselves and contribute materially to the total quantity of lubricating oil which may be recovered from any particular stock.

The petroleum vapors produced in this way pass upwardly and commingle with those produced by partial vaporization of the original stock and are simultaneously rectified in the column 21, to produce the individual lubricating cuts hereinabove referred to.

The foregoing description of my method is for purposes of illustration and not by

way of limitation. It is my intention that the invention be limited only by the appended claims or their equivalent in which I have endeavored to claim broadly, all inherent 5 novelty.

I claim:

1. The method of distilling hydrocarbon oils which comprises passing crude petroleum oil in a confined stream through a zone of 10 heat, heating it in said confined stream to partly vaporize the said crude petroleum, discharging the partly vaporized crude petroleum into a separating zone maintained under vacuum, separating it therein to produce a 15 separated vapor and a liquid residuum, maintaining a body of the said separated residuum, continuously abstracting liquid from the said body, conducting the abstracted liquid in a confined stream through a zone of heat, 20 thereby heating the same, and returning all the heated material to said maintained body.
2. The method of distilling hydrocarbon oils which comprises conducting crude petroleum oil in a confined stream through a zone 25 of heat, heating it therein to a temperature sufficient to partly vaporize the same, discharging the heated oil into a separating zone maintained under vacuum, separating it therein to produce a vapor and an unvapor- 30 ized liquid residuum, maintaining a body of unvaporized liquid residuum, continuously abstracting liquid from the said body, conducting the abstracted liquid in a confined stream thru a zone of heat, thereby heating the 35 liquid abstracted, and returning all the heated material to the said maintained body, the amount of heat thereby introduced being sufficient to maintain the said body at a tempera- 40 ture of 600° to 800° F.
3. The method of distilling hydrocarbon oils which comprises conducting crude petroleum oil in a confined stream through a zone of heat, heating it therein to a temperature sufficient to partly vaporize the same, dis- 45 charging the heated petroleum oil into a separating zone maintained under vacuum, separating it therein to produce a petroleum vapor and a liquid residuum, maintaining a body of said liquid residuum, continuously abstracting liquid from the said maintained 50 body, conducting the abstracted liquid in a confined stream through a zone of heat, heating it in said zone of heat and returning all the heated material to said maintained body, the amount of heat thereby introduced being sufficient to maintain the said body at a tempera- 55 ture at which vapor is actively and continuously evolved therefrom.
4. Method according to claim 1 in which the said maintained body of liquid residuum is in free communication with the said separating zone.
5. Method according to claim 2 in which the said maintained body of liquid residuum

is in free communication with the said separating zone.

6. Method according to claim 3 in which the said maintained body of liquid residuum is in free communication with the said separating zone. 70

7. The method of forming lubricating distillate from crude petroleum oil which comprises conducting crude petroleum oil in a confined stream through a zone of heat, heating it therein to a temperature sufficient to partly vaporize the same, discharging the heated crude petroleum into a separating zone maintained under vacuum, separating it therein to produce a petroleum vapor and a liquid residuum, maintaining a body of liquid residuum in free communication with said separating zone, continuously abstracting part of the said residuum, conducting the abstracted liquid in a confined stream 85 through a zone of heat, heating it therein, returning all the heated material to said maintained body, the amount of heat thereby introduced to said maintained body being sufficient to produce an active and continuous 90 evolution of petroleum vapors therefrom, commingling the vapors so produced with the vapors separated in said separating zone, and rectifying the commingled vapors to produce a series of lubricating distillates. 95

In testimony whereof, I have signed my name to this specification this 5th day of July, 1928.
